(57) **CLAIM**

The ornamental design for a motor module for a conveyor system as shown and described.

DESCRIPTION

FIG. 1 is a front, top, right side perspective view of a motor module for a conveyor system showing our new design; FIG. 2 is a rear, top, left side perspective view thereof; FIG. 3 is a front view thereof; FIG. 4 is a rear view thereof; FIG. 5 is a top view thereof; FIG. 6 is a bottom view thereof; FIG. 7 is a right side view thereof; FIG. 8 is a left side view thereof; FIG. 9 is an enlarged cross-sectional view taken along lines 9-9 shown in FIG. 7; and, FIG. 10 is an enlarged cross-sectional view taken along lines 10-10 shown in FIG. 7.

The broken lines in the drawings are for the purpose of illustrating portions of the motor module for a conveyor system that form no part of the claimed design.

The dash-dot broken lines define the bounds of the claimed design and form no part thereof.
